SANDAL

Iredell M. Smith, Richmond Heights, Mo., assignor to Foot-Sadl, Inc., a corporation of Missouri

Application February 1, 1939, Serial No. 253,982

1 Claim. (CL. 36—11.5)

This invention relates to sandals.

The object of this invention is to provide a sandal which will be simple in construction, economical to manufacture, durable in service, pleasing in appearance, and comfortable to the wearer.

Other and particular objects will be apparent from the following detail description, taken in connection with the accompanying drawings.

Fig. 1 is a perspective view of a sandal embodying this invention;

Fig. 2 is a plan view;

Fig. 3 is a plan view of an outsole assembled with a middle sole and sectional spacing members;

Fig. 4 is an edge view of the parts shown in Fig. 3;

Fig. 5 is a plan view of an insole;

Fig. 6 is a vertical section through the heel portion of the sandal; and

Fig. 7 is a plan view of a quarter member.

The sandal includes generally three parts, a bottom 1, a foot strap 2 and rear quarter members 3 and 4. The bottom 1 has an outsole 5 and an insole 6, preferably of the same configuration, secured together about their periphery by a line of stitches 7. A middle or cushion sole 8 is of less extent than the sole pattern and of such configuration as to lie wholly within the seam 7. The middle sole 8 is spaced above the outsole 5 by means of sectional members 9, 10 and 11, of such form as to provide through openings between the middle sole and outsole, as well as between the insole and outsole, for the insertion of a strap 2.

The outsole and insole are preferably constructed of leather, the middle sole of soft rubber or of sponge rubber, and the spacing members of fiber composition. It will be understood, however, that other and substitute materials may be used. It is preferable, however, to have the middle sole of soft resilient material, although in some aspects of this invention the middle sole may be dispensed with entirely.

A heel 12 may be attached by nails 13. The heel may be of leather, rubber, wood, composition or any other convenient material and attached in any convenient manner, no novelty being claimed in the heel or its manner of attachment.

The quarter members 3 and 4, clearly shown in Figs. 1 and 7, each has serrated lower edges formed with prongs or tongues 14 by slots 15 and being skived to a thin edge. The prongs 14 extend through slots 16 in the insole 6 and outwardly between the insole and outsole so as to be caught by the seam 7. The slots 15 are preferably enlarged at their inner end as shown at 17, Fig. 7, so as to engage edges 18 of the slots 16 in the insole.

It will be understood that the quarter members 3 and 4 are alike except that the member 3 carries a buckle 19 while the outer end of the quarter 4 has an elongated strap with holes to be caught by a tongue of the buckle 19.

The quarters 3 and 4 each have slots 20 to pass the strap 2. In the preferred construction a single strap 2 is used. It has a loop 21 extending between the middle sole and outsole at the ball thereof, a pair of loops 22 extending over the forepart of the foot when inserted in the sandal, a pair of loops 23 extending between the middle sole and outsole at the instep and a loop 24 extending through the slots 20 of the quarters 3 and 4 and about the heel. The ends of the strap may be fastened by a buckle 25 at the ankle.

The strap 2 in passing through the insole inside the seam 7 passes through slots 26 of novel construction. As best shown in Fig. 5, the slots 26 are each formed by a generally longitudinal slit 27 and lateral slits 28 to form tongues 29. As shown in the drawings, the slits 28 may be circular punches but sufficient to form a well defined tongue 29 which lies under and against the strap to form a well finished structure.

It will be obvious that various changes may be made in the details of construction, within the scope of the appended claim, without departing from the spirit of this invention, and that parts 40 of the invention may be used without the whole.

I claim:

In a sandal, an outsole, an insole of the same configuration as the outsole, a cushion middle sole of less extent, a line of stitches uniting the outsole and insole beyond the middle sole, and an upper portion extending through slits in the insole inwardly of the stitches and inwardly beneath the middle sole.

IREDELL M. SMITH
